Inventor -

Walter Jagosz

UNITED STATES PATENT OFFICE

111,514

DESIGN FOR A COMBINED RADIO CABINET, PHONOGRAPH CABINET AND DESK

Walter Jagosz, Detroit, Mich.

Application May 16, 1938, Serial No. 77,230

Term of patent 7 years

To all whom it may concern:

Be it known that I, Walter Jagosz, a citizen of the United States, residing at Detroit, in the county of Wayne and State of Michigan, have invented a new, original, and ornamental Design for a Combined Radio Cabinet, Phonograph Cabinet and Desk, of which the following is a specification, reference being had to the accompanying drawing, forming a part thereof, in which,

Figure 1 is a front elevation of the article, showing my design.

Figure 2 is a side elevation taken on line 2—2 of Figure 1.

Figure 3 is a side elevation taken on line 3—3 of Figure 1.

I claim:

The ornamental design for a combined radio cabinet, phonograph cabinet and desk, as shown.

WALTER JAGOSZ.
